UNITED STATES PATENT OFFICE.

MARY CARION, OF HILLSIDE, NEW JERSEY.

COMBINED IRONING BOARD AND LADDER.

Application filed January 20, 1926. Serial No. 82,576.

This invention contemplates the provision of a combined step ladder and ironing board, wherein each is used singly as a support for the other, the ladder including 5 pivotally mounted members adapted to be arranged in alignment and cooperating with said ladder to support the board, the invention residing in the construction, combination and arrangement of parts as claimed.

10 In the drawing forming part of this application, like numerals of reference indicate similar parts in the several views, and wherein:

Figure 1 is a view showing how the ladder 15 is used as a support for the ironing board.

Figure 2 is a view showing the parts folded.

Figure 3 is a view showing how the ironing board is used as a support for the ladder.

20 Figure 4 is a detail view of one of the rungs of the ladder showing how it is connected with the operating rod therefor.

Referring to the drawing in detail, 10 indicates an ironing board of ordinary construction, and provided at its under side with spaced lugs 11 and spaced blocks 12, each of the latter being provided with notches 13' for a purpose to be presently described. Pivoted on the blocks 11 is a step 30 ladder including spaced parallel side members 13 and steps or rungs 14, the latter being pivoted so they may occupy either of the positions illustrated in Figures 1 and 3. All of these steps 14 are connected by eyes 35 15 to a sliding operating rod 16, whereby all of the steps are simultaneously moved to one or the other of their positions. When the rod is moved in one direction the steps are folded as shown in Figure 1 and held in 40 this position by means of a hook-like element 17 passed through an opening in the adjacent end of the rod 16. When the rod is moved in an opposite direction the steps are extended for use and held in this position by a hook-like element 18 passed 45 through an opening in the adjacent end of said rod. Pivoted on the opposite sides of the ladder are members 19 and 20, respectively, which are adapted to be used in 50 junction with the ladder to support the iron-

ing board 10 in the manner shown in Figure 1. The members 19 are connected by a rod 21, and this rod is adapted to be positioned in the notches 13' of the blocks 12 when the members 19 are swung to the position shown in Figure 1. When the members 20 are arranged in alignment with the members 19 they rest upon the floor, and together with the members 19 and the ladder constitute a support for the ironing board. 55 This arrangement of parts is clearly shown in Figure 1. When it is desired to use the ladder the members 19 and 20 are arranged as shown in Figure 3, wherein the ironing board 10 and the members 19 are used as a 60 support for the ladder. When it is desired to fold the structure the members 19 and 20 are arranged in parallelism with the ladder, and the latter swung against the board 10 as shown in Figure 2. 70

While it is believed that from the foregoing description the nature and advantages of the invention will be readily apparent, I desire to have it understood that I do not limit myself to what is herein shown and 75 described, and that such changes may be resorted to when desired as fall within the scope of what is claimed.

Having thus described the invention, what is claimed as new, is:— 80

In combination, a step ladder, an ironing board pivoted at one end of the ladder, spaced blocks secured to the under side of said board and having aligned notches, a pair of members independently pivoted on 85 the opposite sides of the ladder and adapted to be arranged in alignment and used with the ladder as a support for said board, a cross rod carried by one of said members and adapted to be received by the notches in said blocks, and said last mentioned member being adapted to be arranged at any desired angle with relation to the ladder and singly used with said board as a support for said ladder, and both of said members 90 being capable of being folded at opposite sides of the ladder. 95

In testimony whereof I affix my signature.

Mrs. MARY CARION.
